UNITED STATES PATENT OFFICE.

DAVID SUTTIE McILROY AND WILLIAM GIBB, OF CALGARY, ALBERTA, CANADA.

FLUSH-TANK.

1,140,053.

Specification of Letters Patent. Patented May 18, 1915.

Application filed April 20, 1914. Serial No. 833,281.

To all whom it may concern:

Be it known that we, DAVID SUTTIE McILROY and WILLIAM GIBB, subjects of the King of Great Britain, and both residents 5 of the city of Calgary, in the Province of Alberta, Dominion of Canada, have invented certain new and useful Improvements in Flush-Tanks; and we do hereby declare that the following is a full, clear, 10 and exact description of the same.

The invention relates to improvements in flush tanks for water closets, urinals, drains, etc., whereby an air chamber in the form of a small tank is fixed rigidly inside of a flush 15 tank, having a siphon connection for flushing and an air outlet pipe with a push button valve arrangement for releasing the pressure of the air in air chamber, and an automatic piston check or other valve at the 20 top of the air chamber, operated by a ball float or other automatic means, which seals air chamber until tank is again filled with water, thus avoiding the withdrawal of all the air from the air chamber by the push 25 button valve being held open longer than necessary.

All the parts under water being perfectly rigid, there is practically no liability of any part getting out of working order, nor the 30 attendant wear and tear of movable parts as in the present systems, the whole device being very simple of construction and easy of manufacture.

We attain these objects by means of the 35 mechanism illustrated in the accompanying drawings, in which—

Figure 1 is a sectional view of a flush tank, showing the arrangement of the air chamber, siphon connection and air outlet pipe. 40 Fig. 2 is a top view of flush tank showing the location and arrangement of the different parts.

Similar letters refer to similar parts throughout the various views.

45 A is an ordinary flush tank having rigidly attached to the bottom thereof an air chamber B, with small openings *a* at the bottom to admit the water. Leading into

the air chamber B is a siphon arrangement C, which is also attached to the outlet pipe D at the bottom of the flush tank. Attached to the top of air chamber B is an air outlet pipe E, which comes out through the top of flush tank A, and leads down either end or side of tank as shown by E and *b*, or if necessary can be carried down the wall or any other suitable location. At the far end of the air outlet pipe E is a push button valve F, which releases the air from air outlet pipe E and air chamber B, causing 60 the discharge of siphon C. When the water in air chamber B is discharged, a sufficiency is retained in container G and trap H of the siphon, to seal the air chamber B and secure compression in both air chamber 65 B and air outlet pipe E for the next flush.

Attached to air outlet pipe E at the top of air chamber B is an automatic piston check valve J, operated by a ball float K, or by the water supply ball float by means 70 of a suitable connection, which automatically seals air chamber B, when water is withdrawn from tank A, and prevents the breaking of siphonic action by the push button valve F being held open for too long a 75 time. As the tank A fills with water, the ball float K automatically opens the piston check valve J, in the outlet pipe E, the whole arrangement being then controlled by push button valve F. 80

The ball float K is fitted loosely to rod *c*, and held in place by bolts on the rod, placed on either side of the ball, so that the ball can be moved back and forth, which regulates the time for the opening and closing of check valve J. 85

The water inlet in the tank is similar to that in the ordinary flush tank with the ball float arrangement.

What we claim is:

In flush tanks, a tank having a water inlet and outlet, an air chamber within said tank having water inlets adjacent to the lower end and an air outlet at the upper end an outlet water pipe in S-shape having its inner 95 end projecting upwardly in said air cham-

ber and the other end projecting downwardly to the tank outlet, an air pipe extending upwardly from said air outlet and downwardly to a suitable support, an air 5 valve at the lower end of said air pipe, a float operated valve gear, and an air valve above said air outlet operatively connected with said float valve gear.

Signed at Calgary, Province of Alberta,
Canada, this thirty-first day of March, 1914. 10

DAVID SUTTIE McILROY.
WILLIAM GIBB.
